UNITED STATES PATENT OFFICE

HERBERT E. WILSON, OF ANTRIM, NEW HAMPSHIRE

LUG STRAP AND METHOD OF MAKING THE SAME

Application filed October 28, 1929. Serial No. 402,848.

This invention relates to lug straps for looms and it has for one of its objects to provide a novel method of making a lug strap by which an article with superior 5 wear qualities may be produced and another object of the invention is to provide a novel lug strap having such superior wear qualities.

Lug straps are frequently made of fabric 10 and one way commonly employed in making lug straps of this material is to apply glue or some adhesive to a piece of duck, canvas or other material and then roll this glued piece into the form of a roll. The 15 roll is then put in a press and subjected to heavy pressure to compact the various plies and to so shape the roll that it has a cross-sectional shape such as desired for the completed lug strap. The article is then taken 20 from the press and laid on a drying rack until the glue is partially dry. It is then removed from the drying rack and bent into the U shape necessary for the lug strap and such U shape being preserved until the 25 glue becomes thoroughly dry by placing the lug strap in suitable forms.

The bending of the roll into the U shape after the glue has partially set is detrimental because it is apt to reduce the adhesive 30 properties of the glue. Most kinds of glue will assume a more or less crumbly nature if disturbed when it is partially set and if glue of this nature is used in the making of a fabric lug strap the bending of the roll 35 into the U form will tend to cause the glue to crumble so that it loses much of its efficiency in binding the layers of cloth together and as a result the lug strap is weakened at the bend, which is the point where 40 it should be of maximum strength.

In carrying out my invention I propose to roll the glue saturated cloth up into the form of a roll and while the glue is still warm 45 and before it has cooled I place the roll in a press adapted to mold or shape the roll into the form of a lug strap. The press is designed to apply heavy pressure to the article and this pressure is maintained until the glue has become cool and has firmly set. 50 Since all of the molding operation is ac-

complished while the glue is warm and before it has begun to set this operation is carried out without in any way detracting from the adhesive properties of the glue. The result is that a lug strap made according to my improved method will have its maximum strength throughout and thus will have an increased length of life, this being due to a considerable extent to the fact that the lug strap is given its permanent shape 55 before it is taken from the press and there is no disturbing of the glue after it begins to set.

In making my lug strap I may, if desired, place a reinforcing piece of metal in 60 the center of the roll and make the lug strap with an additional layer or layers of cloth around the bend thereof thereby importing into the lug strap additional strength at the 65 points where it is most needed.

In order to give an understanding of the invention I have illustrated in the drawings some selected embodiments thereof and some of the steps of the method by which it may be made.

Fig. 1 is a perspective view illustrating the operation of rolling up layers of canvas or cloth into the form of a roll from which the lug strap may be made;

Fig. 2 is a perspective view of the roll 80 completed;

Fig. 3 is a perspective view of a leather-reinforcing member which is put in the bend of the lug strap to receive the wear of the picker stick;

Fig. 4 is a more or less diagrammatic view illustrating the press in open position and showing the unmolded lug strap therein, the top and bottom plates of the press being omitted from said view;

Fig. 5 shows the press closed with the lug strap molded therein, the top and bottom plates of the press being omitted for the sake of clearness;

Fig. 6 is a perspective view of the complete lug strap;

Fig. 7 is a section on the line 7—7, Fig. 6;

Fig. 10 is a view through the mold taken on the line 10—10, Fig. 5;

Fig. 11 is a view similar to Fig. 1 but illustrating the formation of a reinforced 5 lug strap;

Fig. 12 is a view similar to Fig. 5 illustrating the press adapted to make the reinforced lug strap, said press being shown in closed position with the lug strap therein;

10 Fig. 13 is a perspective view showing the reinforced lug strap;

Fig. 14 is a section on the line 14—14, Fig. 13;

15 Fig. 15 is a section on the line 15—15, Fig. 13.

A lug strap embodying my invention and which is made in accordance with my improved method is illustrated at 1 in Fig. 6. This lug strap is of the usual U shape, it 20 having the two arms 2 connected by the bridge portion 3, the arms being provided with the usual slots 4. The bend of the lug strap which receives wear from the picker stick is faced with a leather facing 5 and 25 preferably the bridge portion 3 will be formed with a slight convex surface on its inner face as shown at 6.

The lug strap is made from a roll 7 of fabric, such as canvas or duck, the roll being 30 made by rolling up one or more sheets of glue-soaked fabric. As shown in Fig. 1 the roll is made from two sheets 8 and 9 of some suitable fabric, each of which is coated with glue as shown at 10. These 35 sheets are placed one on the other and then are rolled up from one edge as shown at 1 thereby to produce the roll 7. The glue or adhesive 10 which is used will preferably be of the kind which will be liquid when 40 hot but will begin to set as it starts to cool.

The glue or adhesive 10 is applied while hot to the fabric sheets 8 and 9 and they are then immediately rolled up into the roll form shown in Fig. 2. As soon as the roll 45 is formed it is placed in a press which molds it to the shape of the lug strap desired and at the same time places it under heavy compression, the pressure being maintained until the glue has set.

50 While any suitable press suitable for carrying out this work may be employed I have, for the purpose of this application, illustrated a press comprising a core member 11 about which the roll 7 is bent and movable press members 12, 13, 14 which co-operate with the core member 11 to give the roll its lug strap shape. The member 12 is provided with a pressing face 15 which corresponds in shape to the exterior face 55 of the bridge 3. The press members 13 and 14 are shown as hinged to the member 12 at 16 and are adapted to fold toward the core member 11.

60 Fig. 4 shows the press open and in position to receive the roll 7. At the time the

roll is put in the press there will be added the leather facing piece 17 which forms the leather facing 5 of the lug strap. This piece 17 is shown as having chamfered ends 18 and as placed in the press between the members 11 and 12. With the roll 7 and lining member 17 in position shown in Fig. 4 the press will be closed, and during such operation the members 11 and 12 are moved toward each other and the wing members 13 and 14 are closed up toward the core member 11 as shown in Fig. 5.

70 This operation molds the roll 7 and facing piece 17 into the shape of the lug strap as shown in Fig. 5. This molding of the lug strap is accomplished while the glue is hot and before it has cooled or has begun to set.

75 The press is designed to apply heavy pressure to the roll and thus it gives to the lug strap the desired shape as shown in Fig. 6. The pressure is maintained until the glue has cooled and set so that there is no disturbing of the glue or of the fabric or any other part of the lug strap during 80 the cooling or setting operation. It will be understood, of course, that Figs. 4 and 5 show merely the side elements of the mold. The latter will include also top and bottom plates 19 and 20 which serve to give the 85 edges 21 of the lug strap 7 proper shape.

90 The core 11 is preferably formed near its end with the side recesses 22 and at its end it is slightly concave as shown at 23, Fig. 9. The result of this conformation is that when 95 the lug strap is completed it will have the convex faces 24 on the sides adjacent the bridge 3 and said bridge will also have the convex inner face 6. The advantage of 100 these convex faces is that they accommodate 105 themselves to the rocking action of the picker stick and are less subject to wear during use than straight faces would be.

110 In Figs. 11 to 13 I have illustrated how the invention may be employed in making a reinforced lug strap. The lug strap herein shown, which is indicated at 25, has a metal core 26 extending around the U portion thereof, but terminating short of the slots 4. This lug strap is also provided 115 with added thicknesses of cloth around the U portion thereof.

120 In making this lug strap two or more layers of cloth 27, 28 which are coated with hot glue are placed one on the other and a reinforcing layer 29 is also employed. The core member 26 is formed from a piece of strap metal 30 which is preferably slightly longer than the reinforcing piece 29. The 125 parts are superposed one on the other as shown in Fig. 11 and then they are rolled up into roll formation. Such roll formation will have a metal core comprising the metal member 30 and will have a greater 130 number of plies or layers at the center than

at the ends due to the presence of the reinforcing fabric 29.

While the glue 31 which is applied to the faces of these layers of fabric is still hot 5 and before it has had time to set the roll is placed in the press and molded into the desired form, such mold being illustrated in Fig. 12 and comprising the central core portion 32 and the three mold members 33, 34 10 and 35 that are pivoted together are shown at 36. These mold members co-operate in the same way as described with reference to the mold members 12, 13 and 14. Where the extra reinforcing layer 29 is used to provide 15 added thickness of cloth at the bend of the lug strap I propose to recess the inner faces of the mold members 35, 36 as shown at 37 to accommodate this extra thickness.

20 A lug strap made in this way will have the central metal core 26 which extends around the U and substantially to the slots 4 and will also have around the U portion the added thickness of fabric. This added 25 thickness does not extend quite to the end of the metal reinforcing member but it gives added strength and reinforcement to the portion of the lug strap which is subjected to the severest wear.

30 In all forms of the invention the roll is molded into the final shape of the lug strap while the glue is still warm and before it has begun to set and is then subjected to heavy pressure, which pressure is maintained 35 while the glue is drying and setting. There is, therefore, no movement of any part of the lug strap while the glue is cooling or setting and the latter will maintain its full adhesive efficiency.

40 It will be noted that the mold or press is so shaped as to form a lug strap in which the bridge portion 3 is straight transversely. In other words, the inner face of this bridge portion 3, which is the face that acts against 45 the picker stick, is straight in the direction of its length and thus will fit flatly against the picker stick. This is a decided advantage as it reduces the wear on the lug strap.

The important thing about my invention 50 is that the flat face with which the picker stick has engagement is secured without the use of a plug in the bend of the strap. It is a more or less common practice to place such a plug in the curve of the strap to provide 55 the flat face, these plugs being generally riveted in position. My invention provides a flat face and a lug strap which has a long life without the labor and expense involved in riveting the plug in the lug strap.

60 I claim.

1. The improvement in the art of making a lug strap which consists in rolling a plurality of superposed layers of fabric in hot glue to form a roll, placing on one side of 65 the roll at the central portion thereof a

leather facing having skived ends and immediately and while the glue is still warm and before it begins to set, bending the roll and the leather facing into U shape with the leather facing on the inside of the U, and as 70 a final and continuous step of the bending operation molding the bent roll under pressure into the final form of a lug strap and maintaining the layers of fabric and leather under pressure in an undisturbed condition 75 during the entire time that the glue is setting.

2. A lug strap for looms having a general U shape and provided with slots at the ends of its arms, said lug strap being made of a plurality of plies of fabric adhesively united under pressure, there being a greater number of plies at the U portion thereof than in the arms, the inner face of the closed end of the strap being at substantially right angles 80 to the inner faces of the arms of the strap and the inner face at the bow end of the lug strap being convex and said lug strap having a single metallic core extending 85 around the U portion or bow end centrally thereof, the ends of the metallic core terminating 90 between the bow end of the strap and the slots in the arms.

In testimony whereof, I have signed my 95 name to this specification.

HERBERT E. WILSON.
